UNITED STATES PATENT OFFICE.

FRANK S. HEATH, OF CORRY, PENNSYLVANIA.

EVAPORATOR.

No. 852,435.

Specification of Letters Patent.

Patented May 7, 1907.

Application filed May 29, 1906. Serial No. 319,368.

To all whom it may concern:

Be it known that I, FRANK S. HEATH, a citizen of the United States, residing at Corry, in the county of Erie and State of Pennsylvania, have invented certain new and useful Improvements in Evaporators; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to evaporators, and more especially to that class of evaporators for use in making maple syrup and sugar from the sap of maple trees, although it may be used in evaporating liquids of any kind.

20 The object of my invention is the construction of an evaporator having circulation pipes connected to the primary evaporating pan in such a manner as to expose the largest amount of heating surface possible 25 and at the same time permit of constant circulation of the liquid being evaporated.

The features of my invention are hereinafter set forth and explained, and are illustrated in the accompanying drawings, in 30 which:

Figure 1 is a top or plan view of an evaporator embodying my invention. Fig. 2 is a longitudinal section of the evaporator body on the line $x-x$ in Fig. 1. Fig. 3 is a transverse section of the same on the line $y-y$ in Fig. 1. Fig. 4 is a transverse section on the line $y-y$ in Fig. 1, showing a modified construction of my invention. Fig. 5 is a side view of the primary evaporating pan, showing said modified construction of circulation pipes.

In these drawings A indicates the furnace body of an ordinary evaporator, B the primary pan, and C & D the secondary pans.

45 In carrying out my invention I construct the primary pan B with openings in the bottom along each side edge thereof; and in these openings I secure a series of U-shaped circulation pipes E one side e of which is longer than the opposite side e' , see Fig. 3. These U-shaped circulation pipes E extend downward into the fire-box of the evaporator furnace A far enough so that the portions e^2 thereof may, if desired, form the grate-bars for the fire-box. These U-shaped circulation pipes may be secured in the bottom-

plate of the pan B by any well known means, but I preferably secure them therein by forming screw-threads on the ends of said U-shaped circulation pipe and then secure them 60 in the openings in the bottom of the pan B by means of a nut below and above the bottom plate of said pan, with asbestos or other packing between one of the nuts and the pan.

In Figs. 4 & 5 I show an alternative construction of my invention, in which the portions e^3 of the circulation pipes are secured in the pan at their upper ends and their lower ends are secured in a trunk F, and the portions e^4 of said circulation pipes lead from the 65 side of the trunk F across to the opposite side of the fire box and then up to the pan B. From the bottom of the trunks F a drain pipe f leads to a cock f' by means of which the circulation pipes and trunks may be 70 drained when the pan is emptied, which does away with the necessity of tipping the pan bottom side up, as in the construction shown in Figs. 1, 2 & 3. I have shown the circulation pipes E as having one side longer than 75 the opposite side, thereby necessitating the middle or transverse portion of the duct to lie in an ascending position from the long side to the short side of the circulation pipe. This is desirable in order to give an upward 80 flow to the liquid from the lowest point of the circulation pipe. The secondary pans C & D are for the purpose of evaporating the syrup after it has become too dense to be exposed to the direct heat over the fire-box. 85

In operation the sap is first placed in the pan B filling the circulation pipes E therewith. Fire is then placed in the fire-box, preferably upon the portions e^2 of the U-shaped circulation pipes E, and as the portions e^4 and e^2 thereof are nearer the fire than the portions e , the sap therein becomes hotter and flows in the direction of the arrows in Figs. 2, 3 & 4, thereby causing a rapid circulation in said circulation pipes. By means 90 of this invention I am enabled to evaporate the maximum quantity of sap while consuming a minimum quantity of fuel, with no danger of scorching the same.

Having thus fully described my invention, 105 so as to enable others to construct and operate the same, what I claim is:

1. In an evaporator the combination of a furnace body, an evaporator pan over said furnace body, and a series of U-shaped circulation pipes, having both ends thereof in communication with the interior of said pan, and

their intermediate portions extending downward into the said furnace body, substantially as described.

2. In an evaporator, the combination of a furnace body, an evaporator pan over said furnace body, and a series of circulation pipes communicating with the interior of said pan extending downward into the fire-box of said furnace body, the upright portions of each of said circulation pipes being longer on one side than on the opposite side and the portion of said ducts connecting the upright portions being transverse of said fire-box, substantially as described.

3. In an evaporator the combination of a furnace body, a fire-box therein, an evaporator pan over said fire-box, having two rows of alternate openings on the bottom of said pan adjacent to each side thereof, and a series of U-shaped ducts extending downward into said fire-box connecting the outer of each of said openings in the bottom of said

pan with each of the inner openings on the opposite side of said pan, substantially as set forth.

4. In an evaporator the combination of a furnace body, a fire-box therein, an evaporator pan over said fire-box, having a series of down-flow openings arranged adjacent to each side thereof and a series of up-flow openings arranged inside of each of said series of down-flow openings, and a series of circulation pipes connecting each of said down-flow openings with the opposite up-flow openings, the down-flow portion of said pipes being longer than the up-flow portion thereof, substantially as set forth.

In testimony whereof I affix my signature, in presence of two witnesses.

FRANK S. HEATH.
